UNITED STATES PATENT OFFICE

2,439,509

ALARM SWITCH

William C. Eddy, Michigan City, Ind., assignor
to Television Associates, Inc., Chicago, Ill., a
corporation of Illinois

Application February 11, 1946, Serial No. 646,752

3 Claims. (Cl. 200—142)

1

This invention is directed to a switch for use in conjunction with a refrigerating apparatus.

The principal object of this invention is to provide a switch adapted to be placed in the cooling compartment of a refrigerating apparatus for giving an alarm when the temperature therein rises to a predetermined value and wherein the usual thermostatic elements are eliminated.

This invention is particularly useful in quick freeze and cold storage units wherein foodstuffs and the like are frozen and stored. Usually large quantities of foodstuffs and the like are stored in such units and if the temperature therein should rise to values where the foodstuffs would become unfrozen, great damage thereto would result. The switch of this invention, being foolproof in operation, will give an alarm before this dangerous condition can occur and thus permit saving of the foodstuffs and the like stored in the units from damage.

In carrying out this object of the invention the switch comprises electrical contacts for controlling the alarm, a pivoted lever for normally closing the contacts to give the alarm, and a cup carried by the lever and provided with an opening therein to receive frozen material for holding the contacts open, the arrangement being such that upon rise in temperature in the refrigerating apparatus, the frozen material will melt and drain through the opening to permit closing of the contacts. The frozen material may be in the form of an ice cube and in the making of the ice cube various amounts of salt or other material for lowering the melting point thereof may be utilized. In this way the melting point of the frozen material may be determined and hence the temperature of the refrigerating apparatus at which the alarm will be given also determined.

The switch may be a self-contained unit containing the battery and alarm or the electrical source and alarm may be located exteriorly of the refrigerating apparatus.

Other objects and advantages will become apparent to those skilled in the art upon reference to the accompanying specification, claims and drawing, in which—

Fig. 1 is a perspective view of one form of the alarm switch of this invention;

Fig. 2 is a partial sectional view through the cold storage compartment of a quick freeze or cold storage unit showing the alarm switch located therein;

Fig. 3 is an enlarged sectional view taken substantially along the line 3—3 of Fig. 1;

Fig. 4 is a plan view of a modified form of the alarm switch;

Fig. 5 is a schematic wiring diagram.

The alarm switch is generally designated at 10 and it may be located in a cold storage compartment 11 of a quick freeze and cold storage unit

2

generally designated at 12. The cold storage unit may be of conventional form having side walls 13 and 14 made of insulating material. The frozen articles to be stored in the compartment 11 may be piled up therein as shown at 15. The cold storage unit may be provided with an access opening with a suitable cover 16. After the frozen foodstuffs are placed in the cold storage unit, the alarm switch 10 may be set on top of them and, preferably, the alarm switch 10 is located adjacent the top of the unit, as shown in Fig. 2 where the temperature of the unit is usually the warmest.

The alarm switch 10 may comprise a base plate 18 carrying a bifurcated support 19 to which an arm or lever 20 is pivoted by a pivot pin 21. The lever 20 carries a cup 22 provided with an opening 23 in the bottom thereof. When the cup 22 is empty, the weight of the lever 20 is such that it is maintained in the position shown in Fig. 1. When, however, frozen material such as an ice cube 24 is placed in the cup 22, the weight of the lever 20 is overbalanced by the weight of the ice cube 24 to hold the lever 20 in the position shown in Fig. 2.

The lever 20 acts as one electrical contact engaging and disengaging a stationary electrical contact 26 carried by a block of insulating material 27. The contact 26 is maintained in the block 27 by a screw 28. A screw 29 extending through an insulating washer 30 in the base plate 18 screws into the contact 26 so that the screw 29 is electrically connected to the contact 26. A metal strip 31 electrically connects the screw 29 to a screw 32 which passes through insulating washers 33 and 34. A nut 35 clamps the strip 31 in place and a nut 36 provides means for securing a wire in electrical connection with the screw 32.

The base plate 18 may be provided with a clip 38 for carrying a battery 39 having terminals 40 and 41. The base plate 18 may also carry an audible alarm 42 having operating coils 43 and 44. The base plate 18 being made of metal is electrically connected to the lever 20 through the pivot pin 21 and support 19 and is provided with a screw 45 for receiving a wire. The screw 32 and hence the stationary contact 26 are connected by a wire 47 to the terminal 41 of the battery and the screw 45 is connected by a wire 48 to the operating coils of the audible alarm 42, which in turn are connected by a wire 49 to the other battery terminal 40. The electrical wiring connections are schematically shown in Fig. 5, the arrangement being such that when the lever 20 engages the stationary contact 26, the audible alarm 42 is energized and when the lever 20 disengages the contact 26 the audible alarm is deenergized. The battery and alarm mounted on the base 18 may be enclosed in a suitable housing 51.

The frozen material such as the ice cube 28 may include salt or other material for lowering the melting point thereof and by predetermining the amount of salt or other material placed therein, the melting temperature of the frozen material 24 may be predetermined. In this way the temperature at which the alarm may be sounded may be predetermined.

When the cold storage unit is packed with the frozen foodstuffs 15, the alarm switch 10 is placed therein with the frozen material 24 in the cup 22, as shown in Fig. 2. If something should go wrong with the refrigerating apparatus causing the temperature in the cold storage unit to rise to a dangerous point, the frozen material 24 in the cup 22 will melt at the predetermined temperature value and will drain through the opening 23 in the bottom of the cup 22. When this occurs the weight of the lever 20 causes it to engage the contact 26 to sound the audible alarm 42, thereby indicating that proper temperature conditions are not being maintained in the cold storage unit. Having been apprised of this condition a person may then check the unit in adequate time and correct the default in the unit without causing any serious damage to the frozen foodstuffs contained therein.

A slightly modified arrangement is shown in Fig. 4. In this arrangement the battery 39 and the audible alarm 42 are disassociated from the base plate 18 and may be located outside of the cold storage unit 12. Wires 52 may connect the terminals 32 and 45 of the alarm switch to the alarm and the source of electrical energy outside of the cold storage unit.

While for purposes of illustration two forms of this invention have been disclosed, other forms thereof may become apparent to those skilled in the art upon reference to this disclosure and, therefore, this invention is to be limited only by the scope of the appended claims and prior art.

I claim as my invention:

1. A switch adapted to be placed in a refrigerating apparatus for giving an alarm upon rise in temperature in the refrigerating apparatus to a predetermined value comprising, electrical contacts for controlling the alarm, a pivoted lever for normally closing the contacts to give the alarm, and a cup carried by the lever and

provided with an opening therein to receive frozen material for holding the contacts open, the arrangement being such that upon rise in temperature in the refrigerating apparatus to the predetermined value, the frozen material will melt and drain through the opening to permit closing of the contacts.

2. A switch adapted to be placed in a refrigerating apparatus for giving an alarm upon rise in temperature in the refrigerating apparatus to a predetermined value comprising, electrical contacts to be connected to an alarm external of the refrigerating apparatus, a pivoted lever for normally closing the contacts to give the alarm, and a cup carried by the lever and provided with an opening therein to receive frozen material for holding the contacts open, the arrangement being such that upon rise in temperature in the refrigerating apparatus to the predetermined value, the frozen material will melt and drain through the opening to permit closing of the contacts.

3. A switch adapted to be placed in a refrigerating apparatus for giving an alarm upon rise in temperature in the refrigerating apparatus to a predetermined value comprising, electrical contacts for controlling the alarm, a pivoted lever for normally closing the contacts to give the alarm, and a cup carried by the lever and provided with an opening therein to receive frozen material, having a desired predetermined melting point, for holding the contacts open, the arrangement being such that upon rise in temperature in the refrigerating apparatus to the predetermined value the frozen material will melt and drain through the opening to permit closing of the contacts.
